US00D603998S

(12) **United States Design Patent**
Fowler, Jr. et al.

(10) **Patent No.:** **US D603,998 S**
(45) **Date of Patent:** **** Nov. 10, 2009**

(54) **FULL DISTRIBUTION TROFFER
LUMINAIRE**

(75) Inventors: **Wilton L. Fowler, Jr.**, Easley, SC (US);
Martin C. Werr, Easley, SC (US);
Randy K. Lewis, Spartanburg, SC (US)

(73) Assignee: **Hubbell Incorporated**, Orange, CT
(US)

(**) Term: **14 Years**

(21) Appl. No.: **29/311,581**

(22) Filed: **Apr. 24, 2009**

(57) **CLAIM**

The ornamental design for a full distribution troffer luminaire, as shown and described.

DESCRIPTION

FIG. 1 is an enlarged bottom left perspective view of a full distribution troffer luminaire showing our new invention;

FIG. 2 is an enlarged bottom right perspective view of the luminaire illustrated in FIG. 1;

FIG. 3 is a top plan view of the luminaire illustrated in FIGS. 1 and 2;

FIG. 4 is a rear elevational view of the luminaire illustrated in FIGS. 1-3;

FIG. 5 is a left side elevational view of the luminaire illustrated in FIGS. 1-4;

FIG. 6 is a front elevational view of the luminaire illustrated in FIGS. 1-5;

FIG. 7 is a right side elevational view of the luminaire illustrated in FIGS. 1-6; and,

FIG. 8 is a bottom plan view of the luminaire illustrated in FIGS. 1-7.

The broken lines illustrate environmental structure and form no part of the claimed design.

The luminaire is shown broken away to indicate no specific length is claimed.
